Inventor:

Justus A. Traut,

By his Attorney,

F. H. Richards

UNITED STATES PATENT OFFICE.

JUSTUS A. TRAUT, OF NEW BRITAIN, CONNECTICUT.

DESIGN FOR A BUCKLE.

SPECIFICATION forming part of Design No. 21,517, dated May 3, 1892.

Application filed February 17, 1892. Serial No. 421,884. Term of patent 7 years.

To all whom it may concern:

Be it known that I, JUSTUS A. TRAUT, a citizen of the United States, residing at New Britain, in the county of Hartford and State 5 of Connecticut, have invented and produced a new and original Design for Buckles, of which the following is a specification, reference being had to the accompanying drawing, forming a part thereof.

10 In the drawing the buckle embodying my design is shown in side elevation.

The leading feature of my design consists in the representation B, with the oppositely-disposed angular figures b a and a' b' joined 15 at their outer ends at 2 and 4 by a connecting-figure, as 3.

Another feature of my design consists in the representation B, with the angular figures a a' terminating at their lower ends in enlargements 6 and 8, respectively, contiguous 20 to the sides of said figure B, thus giving to the design a distinctive and ornamental appearance.

Having thus described my design, I claim—
The design for a buckle, herein shown and 25 described, substantially as set forth.

JUSTUS A. TRAUT.
